(57) **CLAIM**

The ornamental design for a sterilizer for toothbrush, as shown and described.

DESCRIPTION

The claimed sterilizer for toothbrush will be intended to use in the sanitary goods field. The sterilizer for toothbrush is made from acrylic plastic; The claimed sterilizer for toothbrush shows the effect of mirror using translucent glass (half mirror) material in the center of front side; as shown in FIG. 8, it has the structure that toothbrushes can be placed inside. FIG. 1 is a front and left perspective view of a sterilizer for toothbrush, showing my new design; FIG. 2 is a front elevational view thereof; FIG. 3 is a rear view thereof; FIG. 4 is a left side elevational view thereof; FIG. 5 is a right side elevational view thereof; FIG. 6 is a top plan view thereof; FIG. 7 is a bottom plan view thereof; and, FIG. 8 is a front and right perspective view thereof, shown with the door in open condition.
